AUTOMATIC CONTROL OF AMPLIFICATION

Hans Bartels, Berlin-Spandau, Germany, assignor to Telefunken Gesellschaft für Drahtlose Telegraphie m. b. H., Berlin, Germany, a corporation of Germany

Application October 28, 1935, Serial No. 47,089

In Germany November 5, 1934

9 Claims. (Cl. 179—100.1)

This invention relates to the automatic control of amplifiers utilized in connection with telegraphy, telephony, sound recording and reproducing, radio broadcasting and the like, and has for its principal object the provision of an improved apparatus and method of operation whereby the amplification ratio of such apparatus may be expanded or compressed in response to variation in the volume of the transmitted signal.

Such apparatus has utility wherever the volume of orchestral music or the like tends to exceed the capacity of the apparatus or the capacity of the record track on which the signal is recorded. If for instance the natural signal level varies between 1:1000 the latter may have to be reduced to 1:50 for making record plates. This value is determined by the established groove distance and the noise level. The loudest parts of the lowest frequencies should not serve to cut through the matrix between the grooves. Furthermore, the steepness of the cut sound groove should not become too great at large volume, since in this case the plate can no longer be played without objectionable distortion. The conditions are still less favorable in case of the talking film where it is necessary in view of the noise of the film to reduce the range of amplification to an essentially greater extent than in the case of record plates.

It has been determined that for controlling the amplification range automatically without disturbance or distortion, such transmission arrangements for transmitting orchestra performances, for instance, require extremely short building up periods for amplification control. The dying out periods may be 10 to 20 times as long as the building-up periods. For dimensioning the required time constant for the control the following points are of importance:

Upon a sudden transition from the softest to the loudest parts, there always occurs excessive control to a greater or less degree, especially in sound recording arrangements. These and other disturbances are avoided if the building-up period is less than twenty thousandths of a second (20 m sec.). This fact has been ascertained in such manner that record plates especially selected as to the most favorable performance have been played through a loudspeaker and across an amplifier. By means of a mechanically controlled switching arrangement a detector has been placed in parallel to the loudspeaker, and in this way very high and non-linear distortions were produced. The building-up period of this detector was varied between 5 and 500 m sec. It

was found from a large number of persons used for the tests that up to a switching-in period of approximately 50 to 60 m sec., no distortions whatsoever were discernible. However, it was found that in continuing these tests over a longer period of time, these periods became essentially shorter since the observers became more attentive to the disturbances.

Additional tests were carried out with pure sine tones whereby a buzzer tone of 800 cycles per second (800 Hz) was supplied to the input of the amplifier, and during a short period of time a second buzzer sound of 1000 Hz was added by means of the afore-mentioned switching arrangement in such a manner that the amplitude of the fundamental oscillation was thereby not changed. Hearing tests carried out with this arrangement proved the conditions to be essentially worse. Already at a building-up period of approximately 20 m sec. the disturbing action of the artificially produced non-linear distortion was noticeable. Since non-linear distortions are often encountered in practice (at ordinary excess control of an amplifier, pick-up, sound-recorder and the like, the second harmonics often appears with high amplitude), it is of particular importance to so dimension the control circuit that the building-up period will be less than 20 m sec.

Such short building-up periods as have not been used hitherto for automatic volume control arrangements, are not only necessary for record plate recording arrangements for physiological reasons, but also for purely technical reasons. Thus if the building-up period is assumed to be 100 m sec., and a very loud tone of for instance 50 Hz should be recorded suddenly, this signifies that 100 m sec. will have to pass before the control action begins. However, during 100 m sec. already 10 alternations of the tone of 50 Hz have passed so that at maximum the band of the record plate between two grooves has been broken through 10 times. Hence the record is useless. At a building-up period of 20 m sec. only the first half wave has practically been recorded into the adjacent groove, whereas the second alternation has been already controlled and in all probability the band between the grooves of the record plate will no longer be destroyed. It will be apparent from the foregoing that in order to effectively prevent cutting it through the band between the grooves at more than one point, the volume control should respond within a time of the same order of magnitude as the time of vibration of the sound waves to be recorded, and preferably should respond in a time of one-half

- of the time of a sound wave in order to prevent the other half wave from over-cutting.
- In conflict with the requirement of providing short time constants in the control arrangements, is the demand of noiseless performance. To smoothen the performance it is necessary to use filter elements of comparatively large dimensions. However, such filter elements introduce a large time constant into the control arrangement. Hence filter elements of smaller dimensions should be used whereby, however, only insufficient filtering can be obtained. The appearing disturbing voltages are then to be eliminated in a different manner. In accordance with the present invention this is accomplished in that the control elements are applied to the amplifier in the form of a bridging circuit. With this bridging circuit the upper harmonics appearing due to insufficient filtering as well as other disturbing voltages are prevented from passing into the useful circuit. To avoid unsymmetrical conditions among the elements forming the bridging circuit the one or the other one of the elements is rendered adjustable.
- The invention will be better understood from the following description when considered in connection with the accompanying drawing, and its scope will be pointed out in the appended claims.
- Referring to the drawing:
- Fig. 1 is a wiring diagram of an apparatus which operates on the straight part of its characteristic operating curve at high current to reduce the amplification ratio, and
- Fig. 2 is a wiring diagram which operates similarly to reduce the amplification ratio.
- Fig. 1 illustrates one form of the invention in which non-linear resistances in the form of dry rectifiers are utilized as control devices. It is obvious that the said rectifiers may also be replaced by other non-linear resistances or by tubes, in which case the circuit is to be adapted to the changed operating conditions. The impulses transmitted from the generator 1 through a resistance 2 are branched off and supplied to an auxiliary rectifier 3 which, in connection with the capacity 4 and resistor 5, provides an adjusting direct potential dependent upon the mean amplification level or signal volume for the control rectifiers 6 and 7 connected across the amplification channel. The resistor 8 forming a bridge circuit together with the control rectifiers 6 and 7 is divided into approximately equal parts by the tap at 9 for the purpose of forming the bridge, so that the points 10 and 11 have the same potential relative to the potential at the points 12 and 13. A biasing source 14 is provided so as to enable adjustment to the proper working point of the current-voltage characteristic of the control rectifiers which is important for the dynamic control. The tap 9 of the resistor 8 is preferably made adjustable to compensate unsymmetrical conditions of the individual elements of the bridge such as inequalities of the rectifier resistances. Obviously, the resistor 8 may be substituted by two separate variable resistors.
- In reducing the amplification ratio, the arrangement of Fig. 1 has the advantage that at high amperages it operates on the straight part of the detector characteristic. If high potentials are produced at the points 12 and 13 due to large volume, it happens, as can be readily seen from the known detector characteristic, that the resistance of the detectors 6 and 7 i. e. the resistance of the bridge between the points 10 and 11 will be decreased.
- In order to have the same advantages with an increase of the amplification ratio, the circuit of Fig. 2 may be utilized. As in the embodiment of the example according to Fig. 1, the control impulses are branched off from the input circuit and are applied to the arrangement 3, 4, 5 and 14 which furnishes the displacement or control potential. The detected impulses are applied at points 20 and 21 of the bridge circuit 22, the latter consisting of detectors 23, 24 and resistor 25 with tap 26. In order that at large volume the arrangement operates on the straight part of the detector characteristic, the amplification train is bridged by a resistor 27.
- At high amplitudes of the alternating potential the resistance of the detector bridge becomes low. Consequently the voltage drop through the resistor 27 will be increased. As in the circuit according to Fig. 1, also at increase in dynamic at higher amplitudes of the alternating potential, the resistance of the detector bridge will be decreased. In other words, the straight part of the characteristic of the detectors is utilized in both cases.
- In the two examples the alternating potential required for the production of the displacement potential is derived ahead of the control member. Obviously this potential can also be tapped in back of the control device. The dimensioning of the individual members of the arrangement of the auxiliary detector should then be altered correspondingly. In case where the branched-off control impulses should prove to be too low, suitable amplifying means can be placed at an appropriate place in front of or in back of, the control detector.
- In view of the control curves, the resistance of the detector is to be high as compared with the bridge resistance (8 and 25). Eventually, it may be useful to place in parallel to the detectors preferably variable resistors thus providing means of influencing the characteristic of the detectors.
- What is claimed is:
1. An amplification ratio control device including a bridge element comprising a resistor and a pair of rectifiers, a pair of terminals connected to said bridge element respectively at a point between said rectifiers and to an intermediate terminal of said resistor, and means operable to apply to the end terminals of said resistor a potential which varies as the volume of the signal supplied to said terminals.
  2. An amplification ratio control device including a bridge element comprising a resistor and a pair of rectifiers, a pair of terminals connected to said bridge element respectively at a point between said rectifiers and to an intermediate terminal of said resistor, and means including a rectifier connected to a resistor through a potential source for applying to the end terminals of said resistor a potential which varies as the volume of the signal supplied to said terminals.
  3. An amplification ratio control device including a bridge element comprising a resistor and a pair of rectifiers, a pair of terminals connected to said bridge element respectively at a point between said rectifiers and to an intermediate terminal of said resistor, and means including a rectifier connected to a resistor through a potential source for applying to the end terminals of said resistor a potential which varies in a time of not more than twenty one-thousandths of a second as the volume of the signal supplied to said terminals.
  4. An amplification ratio control device in-

cluding a bridge element comprising a resistor and a pair of rectifiers, a pair of terminals connected to said bridge element respectively at a point between said rectifiers and to an intermediate terminal of said resistor, and means operable to apply to the end terminals of said resistor a potential which varies in a time of the same order of magnitude as the time of a sound wave as the volume of the signal supplied 10 to said terminals.

5. An amplification ratio control device including a bridge element comprising a resistor and a pair of rectifiers, a pair of terminals connected to said bridge element respectively at a point between said rectifiers and to an intermediate terminal of said resistor, and means including a rectifier connected to a resistor through a potential source for applying to the end terminals of said resistor a potential which 15 varies in a time of the same order of magnitude as the time of a sound wave as the volume of the signal supplied to said terminals.

6. An amplification ratio control device including a bridge element comprising a resistor and a pair of rectifiers, a pair of terminals connected to said bridge element respectively at a point between said rectifiers and to an intermediate terminal of said resistor, and means operable to apply to the end terminals of said 20 resistor a potential which varies as the volume of the signal supplied to said terminals and with a building up time of not more than twenty one-thousandths of a second.

7. An amplification ratio control device including a bridge element comprising a resistor

and a pair of rectifiers, a pair of terminals connected to said bridge element respectively at a point between said rectifiers and to an intermediate terminal of said resistor, and means including a rectifier connected to a resistor 5 through a potential source for applying to the end terminals of said resistor a potential which varies as the volume of the signal supplied to said terminals and with a building up time of not more than twenty one-thousandths of a 10 second.

8. An amplification ratio control device including a bridge element comprising a resistor and a pair of rectifiers, a pair of terminals connected to said bridge element respectively at a point between said rectifiers and to an intermediate terminal of said resistor, and means operable to apply to the end terminals of said resistor a potential which varies as the volume 15 of the signal supplied to said terminals and with a building up time of the order of the time of a single sound vibration.

9. An amplification ratio control device including a bridge element comprising a resistor and a pair of rectifiers, a pair of terminals connected to said bridge element respectively at a point between said rectifiers and to an intermediate terminal of said resistor, and means including a rectifier connected to a resistor through 20 a potential source for applying to the end terminals of said resistor a potential which varies as the volume of the signal supplied to said terminals and with a building up time of the order of the time of a single sound vibration.
